UNITED STATES PATENT OFFICE.

GEORGE W. MEYERS, OF CHICAGO, ILLINOIS.

FLOOR-TREATING MACHINE.

1,164,740.

Specification of Letters Patent.

Patented Dec. 21, 1915.

Application filed December 26, 1913. Serial No. 808,767.

To all whom it may concern:

Be it known that I, GEORGE W. MEYERS, a citizen of the United States, residing at Chicago, in the county of Cook and State of Illinois, have invented a certain new and useful Improvement in Floor-Treating Machines, of which the following is a specification.

My invention relates to floor treating machines, by which I mean to include machines for scrubbing, polishing, grinding, or otherwise treating the surface of floors, be they of wood, stone, mosaic, or of other material.

In the type of machine selected to illustrate the invention, the apparatus is operated chiefly by the aid of electricity, although the machine is controlled by an operator, and the operator, if he desires, may, in addition to controlling the machine, contribute part of the force for advancing it over the floor.

In general, my machine comprises a truck whereon the operative parts are mounted and a handle by which the truck and operative parts may be guided and controlled. The operative parts include, among other things, a rotating frame carrying the brushes or polishers, and this frame is driven by an electric motor. The motor, in addition to driving the brush carrying frame, also drives tractor wheels by which the truck is advanced over the floor. The truck also carries a reel for storing the supply cord by which the electric current is furnished to the machine; and in my machine means are provided for driving the reel in the direction to take up the cord and means are also provided for evenly distributing the cord upon the reel as the cord is wound upon it.

The general object of the invention is to provide a machine which is, practically speaking, completely automatic except as it requires guiding by the operator to such parts of the floor as require to be treated. The manner in which this general object is accomplished will become apparent as the description proceeds.

I accomplish my objects by the mechanism illustrated in the accompanying drawings, in which—

Figures 1 and 2 are respectively side and plan views of the complete machine. Fig. 3 is a sectional elevation looking toward the left from the line 3—3, Fig. 1. Fig. 4 is a

sectional elevation on the line 4—4, Fig. 2. Fig. 5 is a plan view on the line 5—5, Fig. 4. 55 Fig. 6 is an enlarged sectional elevation through the brush and brush carrier on the line 6—6, Fig. 5. Fig. 7 is a plan section on the line 7—7, Fig. 6. Fig. 8 is a plan section on the line 8—8, Fig. 3. Fig. 9 is 60 a side view of the shifting nut which produces the travel, back and forth, of the carriage which distributes the supply cord upon the take-up reel.

Similar numerals refer to similar parts 65 throughout the several views.

In the particular design of machine here shown the truck or main frame consists of an irregular member 1 which is preferably made in a single piece and formed of malleable iron. This frame is supported upon casters 2 and tractor wheels 3. Said tractor wheels are mounted upon the tractor shaft 4 which is power driven in the manner presently to be described. Said tractor wheels 75 are not rigidly connected to the shaft in the best design but are so connected that when the shaft rotates it will drive the wheels but will not prevent them from being rotated faster than the shaft. The details are best 80 shown in Fig. 3, where it will be seen that the body of the wheel consists of two flanged disks 3^a, 3^b fastened together by bolts 5 or other suitable fastening devices and provided with rubber tires 3^c. Said disks are 85 loose upon shaft 4. The inner disk 3^b is provided with internal ratchet teeth 3^d, which coöperate with pawls 6 pivotally mounted upon a pin 7 projecting from the adjacent disk 8 which is keyed or otherwise rigidly 90 secured to shaft 4. The ratchet teeth face in such direction as to drive the machine forward (toward the left, Figs. 1 and 2).

Shaft 4 is driven by a sleeve 9 which is keyed or otherwise fastened to it and which 95 in turn has splined upon it a clutch sleeve 10 adapted to coöperate with clutch teeth 11 formed upon the adjacent surface of a worm gear wheel 12 which is loose upon sleeve 9. Sleeve 10 is shifted into and out of connection with wheel 12 by means of a collar 13 pivotally connected to one end of a lever 15. Said lever is fulcrumed upon the shaft 16 mounted in the frame 1, as best shown at the bottom of Fig. 3. The lever is operated by 105 a rod 17 connected at its upper end to an

arm 18 pivoted upon the pin 19 near the upper end of one of the handles 20. Said arm 18 is controlled by the small hand lever 21, as best shown in Figs. 1 and 2.

5 The arms 20 just mentioned rise to a convenient height from the rear end of the main frame and serve as means whereby the machine may be guided and controlled.

Power is imparted to the tractor shaft 10 and to the gear wheel 12 by a worm 25 which meshes with gear 12 and is fastened to a shaft 26 provided with a bevel gear 27 meshing with the bevel gear 28, as best shown in Fig. 4. Gear 28 is driven by reduction gearing housed in a casing 29 supported upon the main frame 1. Reduction gearing of any suitable type may be employed, and as these devices are known there is no necessity here of showing or describing the same further than to say that the power therefor is furnished by the motor shaft 30 which revolves at a high rate of speed. The reduction gearing is so designed as to greatly reduce the speed in the bevel gear 28. Shaft 30 is driven by an electric motor 31 supported in a frame 32 mounted upon the main frame 1, as best shown in Fig. 1.

Referring now more particularly to the parts which act upon the floor, and to the parts by which they are actuated: The brushes 35 are fastened in brush holders 36 shown in detail in Figs. 6 and 7. In the preferred form these brush holders are open 35 at the end so that the back of the brush may be readily slipped into or out of the holder; and the brush is secured by a set screw 37 or other suitable clamping device. Rising from the brush holder is a stem 38 carrying 40 a washer 39 which forms an abutment for a compression spring 40 which encircles a reduced portion of the stem 38 and is put under compression by an adjusting nut 41 which screws into the top of a housing 42 in which the stem and spring are inclosed. Nut 41 forms a guide for the stem and the downward movement of the stem is limited by a pin 43 which passes through the stem and overlies the nut. As a result of this 45 construction the brush is constantly urged toward the floor with any desired degree of force. Ordinarily a fluid of some kind (oil, water, soap or abrasive) will be used in connection with the machine, and in order to 50 confine this liquid within the acting area of the machine it is desirable to place squeegees 70 of rubber or other suitable material adjacent to the brushes on the outside thereof as shown in Figs. 4 and 6. These in their 55 rotary movement keep throwing the liquid inward into the path of the brushes. The manner in which the liquid will be thrown inwardly can be varied by varying the angle of inclination of the brushes and 60 squeegees with respect to the ring 44 where-

on they are supported. I accomplish this angular adjustment by the means shown in Figs. 6 and 7. A rib 71 is formed upon the side of the stem and this slides in any one of a number of key-way slots 72, 72 formed 70 at the lower end of housing 42. This permits the stem to rise and fall but holds it in any angular position to which it may be adjusted. Thus the brushes may be held at any desired angle relatively to their temporary direction of travel.

In the construction shown the housings 42 are eight in number, and by preference they form an integral part of the ring 44. This ring, together with the parts which it supports and the parts which support it may be conveniently termed the brush carrier. Inwardly extending from ring 44 are arms 45 which are furnished at their inner ends with upstanding guide pins 46. These pins fit 85 loosely in the ends of the arms of a spider 47 which is keyed or otherwise rigidly secured to the shaft 48. Said shaft is fastened to the bevel gear 28 and is therefore driven by the motor through the medium of 90 the reduction gearing. It will be noted that as a result of this construction in which the guide pins 46 are loose in spider 47, the pins cause the brush carrier to rotate and yet permit the carrier to "float"; that is, to move 95 vertically to automatically accommodate itself to inequalities in the floor. In order to reduce friction spider 47 is provided with two sets of bantam bearings 50, 50, interposed between the spider and adjacent parts 100 of the main frame.

When the machine is used as a scrubbing machine water and soap will ordinarily be used. A reservoir 51 for carrying water is provided with a delivery pipe 52 which conducts the water to a convenient point near the center of the machine. The flow of water through the pipe is controlled by a valve 53 fastened to a rod 54 connected to and operated by an arm 55 pivoted upon the pin 19 105 previously mentioned. Arm 55 is here shown to be integral with the arm 18 and lever 21 and the parts are so arranged that as soon as the clutch 10 is thrown in the valve 53 will be opened and will let the water flow. 110 A spring 56 normally urges lever 21 to a position to hold valve 53 closed and clutch 10 disengaged. The reservoir is provided with an outlet valve 62 and this is operated by a cord or chain 63 attached at the far end to 115 the rod 17. The soap or other cleanser or abrasive is delivered in constant quantity by a screw conveyer 64, shown in Figs. 1 and 4. Said conveyer is driven by a shaft 65 having a bevel gear 66 which meshes with the 120 bevel gear 28 previously mentioned.

Now referring to the means for storing and handling the lamp cord or other conductor by which electrical energy is supplied to the machine from a stationary socket some- 130

where in the wall or baseboard of the room where the machine is to be used: The reel cylinder 80 is secured to parallel disks 81, 81 which form the ends of the reel. One of these disks is pinned or otherwise secured to a flanged sleeve 82, as shown at the left of Fig. 3. Said sleeve is journaled in a sleeve 83 which is preferably integral with a sheave 84 journaled in one of the two frame plates 85, 85. Said plates are supported upon the horizontal bars 86, 86 which form part of the frame-work of the machine as best shown in Fig. 1. The plates 85 are braced by tie rods 87 and bars 88, the latter also serving the purpose of supporting and guiding the cord distributor hereinafter described. The sheave 84 just mentioned is driven by a belt 90 which passes over the sheave 91 shown in section at the bottom of Fig. 3 and in dotted lines at the bottom of Fig. 1. Sheave 91 is keyed or otherwise fastened to the tractor shaft 4. A friction disk 92 is interposed between sheave 84 and the flange of sleeve 82 as shown in Fig. 3. This is for the purpose of yieldingly transmitting the rotary movement of the sheave to the reel and causing the winding in of the cord 93. It will be seen that the connection between the sheave and the reel is not a positive one, and if the supply cord is taut it holds the reel against rotation. In fact, the machine may move away from the point of attachment of the lamp cord to the building and thus cause the reel, acting under the tension of the cord, to rotate backward and permit the cord to be drawn off the reel. The construction permits the machine to travel either toward or away from the stationary point of attachment of the supply cord and yet the cord is at all times kept taut.

The supply cord is connected at the inner end to the motor terminals in a manner which I will now describe: The inner ends 93^a of the cord lead into the center of the reel as shown in Fig. 3. At the drum axis they are connected by binding screws 94 to heads 95 formed at the inner ends of binding posts 96 which are arranged horizontally, coincident with the drum axis and journaled in bushings 97 of insulating material. As a result the binding posts rotate in unison with the reel, being pulled around by the inner ends of the cord itself. The binding posts 96 pass out through the plates 85 to terminal blocks 98 which are loosely mounted upon said posts 96 and receive the ends of wires 99 which lead to the terminals on the motor. The wires 99 are indicated in Fig. 3 and are shown diagrammatically in Fig. 2.

I will now describe the means whereby the supply cord is evenly distributed upon the reel: A sprocket wheel 100, best shown in Fig. 3, is keyed to the projecting end of the sleeve 83 and hence rotates in unison

with the reel. A link chain 101 connects sprocket 100 with a sprocket 102 fastened to the distributor shaft 103 which is journaled at the upper end of the plates 85. Rigidly secured to or integral with shaft 103 is a screw 104 which has both right and left screw threads or channels 105 formed therein. A nut 106 shown separately in Fig. 9 and also shown in Figs. 3, 4 and 8 is provided with two helical ribs 107, 108 located on opposite sides of said screw. Said nut slides horizontally in a guide 110 formed in a plate 111. The ribs 107, 108 are far enough apart so that only one of them enters a groove 105 at a time. When the nut is shifted to one position in its frame 111 the rib 107 enters one of the grooves 105 and causes the nut and plate 111 to travel in one direction lengthwise of screw 104. When the nut is shifted to the opposite position it brings rib 108 into the other groove 105 and causes the nut and plate 111 to travel in the return direction. Hence, while the screw continues to rotate in the same direction the plate 111 will move either back or forth along shaft 104 depending upon which of the ribs is in engagement with the screw. Nut 106 is automatically shifted at the end of its travel by means of stationary stops or pins 113, 114 which are in position to engage opposite sides of the cam 115 formed upon the top of the nut. The construction is such that when the nut reaches one end of the screw, the pin 113 will strike cam 115 and shift the nut into engagement on the opposite side of the screw and hence change the direction of travel of the nut. When the nut has arrived at pin 114 said pin will engage the cam on the opposite side thereof and shift the nut and cause it to reverse its direction of travel along the screw. The plate 111 which travels with the nut is secured by shafts 116 to a similar plate 117, said plates forming the frame-work of a carriage which is supported upon and guided by the bars 88, previously mentioned. Supported upon the shafts 116 are guide sheaves 120 which receive the cord 93 and guide it onto the reel. As best shown in Figs. 1 and 4 these sheaves are located opposite to each other so that they may receive and guide the cord no matter in what direction the machine is traveling. As the reel is positively geared to the screw 104 it follows that the guide carriage 111, 117 will travel across the reel in one direction or the other whenever the reel rotates; furthermore, the carriage will always travel in the proper direction, for it is evident that, assuming the carriage to be in the middle of screw 104, if the reel rotates one way the carriage will travel in one direction but if the reel rotates the opposite way the carriage will travel in the opposite direction. Hence, whether the supply cord is being

wound up or unwound the distributing carriage will properly perform its function but will stand still whenever the reel stands still.

The operation of the machine will be apparent from the foregoing description. As soon as the operator turns on the electric current and grasps the handles 20 and lever 21 the motor will start, the water will start to flow through the pipe 52, the valve 62 will be opened to permit the abrasive compound to flow and the clutch 10 will be thrown in. The rotation of the motor will not only cause the brush carrier to rotate but will drive the tractor wheels 3 and cause the machine to advance under its own power at a steady and uniform rate. The rotation of the tractor wheels will cause the reel to revolve and the distributing carriage to travel, the machine being consequently automatic and self-operating except as to the guiding of the machine, which of course, requires the intelligence of an operator. As soon as the operator lets go the handle, the spring 56, (see Fig. 1) will throw the clutch 10 out and will shut off the supply of water and abrasive.

Having thus described my invention, what I claim as new and desire to secure by Letters Patent, is

1. In a floor treating machine, the combination of a frame rotating in a horizontal plane, a brush holder driven by said frame and means for holding said brush holder in different positions with respect to the momentary direction of travel of the brush holder. 30

2. In a floor treating machine, the combination of a frame rotating in a horizontal plane, and a brush holder having a stem provided with a vertical feather, said frame 40 having a plurality of vertical slots each for receiving said feather to hold said stem and the brush holder at various angles relatively to the momentary direction of travel of the brush holder. 45

In witness whereof, I have hereunto subscribed my name in the presence of two witnesses.

GEORGE W. MEYERS.

Witnesses:

HOWARD M. COX,
KATHRYN S. READY.
